UNITED STATES PATENT OFFICE.

ARTHUR J. MOXHAM, OF JOHNSTOWN, PENNSYLVANIA.

ROLL FOR STREET GIRDER-RAILS.

SPECIFICATION forming part of Letters Patent No. 321,627, dated July 7, 1885.

Application filed April 29, 1885. (No model.)

To all whom it may concern:

Be it known that I, ARTHUR J. MOXHAM, of Johnstown, in the county of Cambria and State of Pennsylvania, have invented a new and useful Improvement in Rolling Girder-Rails for Street-Railways, which invention or improvement is fully set forth and illustrated in the following specification and accompanying drawings.

10 The object of this invention is to provide a small number of sets of rolls in train, capable of rolling at least three forms of girder-rails, and thus to avoid entirely any change of rolls, whether all or any of said rails be rolled.

15 The invention consists in certain groupings of passes in the several sets of rolls, so that the metal for different forms of rails, after being put through a number of passes to form a bar or rail of primary shape, is thereafter 20 rolled through other and different special passes, according to the special form of rail desired.

In the accompanying drawings Figure 1 25 illustrates one set of rolls provided with passes numbered from 1 to 6, inclusive. Fig. 2 illustrates a second set of rolls provided with passes numbered from 7 to 13, inclusive. Of said passes all are side passes except Nos. 2 and 4, which are dummy passes.

30 The rolls A and B, respectively upper and lower rolls, illustrate sets of rolls "two high," but may be made "three high," if preferred. In said rolls passes Nos. 9, 11, and 13 are all passes for making rails of finished forms of cross-section—that is, if desired, a rail having the cross-section indicated by pass No. 9 35 may be rolled from the bloom by commencing at pass No. 1 and successively rolling the metal in each pass until No. 9, inclusive, is

40 reached and the metal run through it, when the rail thus rolled may be put to any use required; but if either of the forms of rails indicated by the passes Nos. 11 and 13 be desired, then the rail just turned out of No. 9 serves as 45 a primary form out of which either of the forms of rails indicated by said passes Nos. 11 and 13 is to be rolled.

The whole operation of rolling for all three 50 of said forms of rails is as follows: If it be desired to roll a girder-rail having the shape or form of cross-section indicated by pass No. 9,

the hot-metal bloom of either iron or steel is first run through pass No. 1, then through each succeeding pass up to No. 9, inclusive, the bar thus formed being rolled upon its side in all of said passes, except in passes Nos. 2 and 4, in which, being dummy passes, it is rolled "on the flat." This operation so far completes one finished form of rail indicated by pass No. 9, as hereinbefore explained. 55

If it be desired to roll a center-bearing girder-rail having the shape or form of cross-section indicated by pass No. 11, the shape as formed in pass No. 9, ceasing to be regarded as a finished rail, is immediately thereafter run 60 in and through pass No. 10, the effect of which pass is to partially elongate the metal previously formed at the point *a*, No. 9, by rolling it out into the shape shown at *a'*, No. 10, at the same time partially elongating by rolling or reducing in thickness the point *b*, previously formed in No. 9, to the shape shown at *b'*, No. 10, and also at the same time partially displacing the point *b'* and throwing it 65 nearer into line with the point *b''*, No. 10. This 70 specially described action is further continued by the same *modus operandi* in the changes effected by the next rolling in pass No. 11—that is to say, the point *a'* is further elongated, as shown, to the shape *a''*, and the point *b'* 75 further partially elongated and partially displaced to the point *b'''*, the result being the finished rail indicated in cross-section by pass 80 No. 11. It will be here observed that at the same time in No. 11 a sufficient amount of 85 "draft" or work is distributed over the rest of the surface or whole contour of the girder-section to reduce any tendency in the rail to warp or twist to a minimum or to not exceed practical limits. 90

If it be desired to roll a side-bearing girder-rail having the shape or form of cross-section indicated by pass No. 13, the shape as formed in pass No. 9, ceasing to be regarded as a finished rail, is immediately thereafter run in and 95 through pass No. 12, the effect of which pass, it will be noted, is that the point *b*, previously formed in No. 9, will be partially displaced by being thrown over nearly in line with the point *c* in Nos. 9 and 12, and also partially 100 elongated by being rolled down at the same point as shown at *b'*, No. 12. The further

changes effected by next running this partially-formed rail into the last pass, No. 13, are as follows: The specific action of pass No. 13 is concentrated at the point b^6 , where the effect 5 is entirely that of elongation or reduction by rolling, there being no further displacement pure and simple. The rail therefore emerges from pass No. 13 having a form of cross-section indicated by said pass.

10 In said passes Nos. 12 and 13, as already described in passes Nos. 10 and 11, there is also sufficient "draft" or work distributed over the whole contour or surface of the rail 15 to reduce any tendency to warp or twist to a minimum or to not exceed practical limits. Said draft is not uniformly, though properly, distributed in said passes.

It will be observed that in this invention the two rails indicated by passes Nos. 11 and 20 13 are each rolled from the same primary form of bar, which itself is rolled directly from the hot bloom, and may be or not itself a finished form of rail, as may be desired.

Of course a different distribution of passes 25 may be made, if desired, without departing from the principle of this invention—that is, more or less of the whole number of thirteen passes may be put either into one or more sets of rolls; but the division of passes shown in 30 the two sets of rolls illustrated in Figs. 1 and 2 is considered to be the most judicious in practice.

Having thus fully described my said improvements in rolling rails, as of my invention I claim—

35

1. In a roll-train of one or more sets of rolls, a series of passes substantially of the respective conformations shown from Nos. 1 to 9, inclusive, whereby a bar or rail may be rolled having a cross-section indicated by said pass 40 No. 9, and of a primary form adapted for immediate further rolling, while hot, into other described shapes, substantially as and for the purposes set forth.

2. In a roll-train of one or more sets of rolls, 45 a series of passes substantially of the respective conformations shown from Nos. 10 to 13, inclusive, next succeeding another series of passes substantially of the conformations shown from Nos. 1 to 9, inclusive, whereby 50 either one of three shapes of rails may be rolled from the same bloom, the shape indicated by pass No. 9 being first rolled as a primary to the other two—namely, the shapes respectively indicated by the passes Nos. 9, 55 11, and 13—substantially as and for the purposes set forth.

ARTHUR J. MOXHAM.
